UNITED STATES PATENT OFFICE.

ARTHUR L. WING AND ANDREW NORTON, OF BOSTON, MASSACHUSETTS.

IRONING-MACHINE.

SPECIFICATION forming part of Letters Patent No. 612,762, dated October 18, 1898.

Application filed January 20, 1898. Serial No. 667,238. (No model.)

To all whom it may concern:

Be it known that we, ARTHUR L. WING and ANDREW NORTON, citizens of the United States, residing at Boston, in the county of 5 Suffolk and State of Massachusetts, have invented new and useful Improvements in Ironing-Machines, of which the following is a specification.

This invention relates to improvements in 10 mangles or ironing-machines, and it is particularly well adapted for mangling or ironing bedclothes, table-cloths, towels, napkins, or other flat goods that do not require starching, and it is carried out as follows, reference being had to the accompanying drawings, wherein—

Figure 1 represents a top plan view of the machine. Fig. 2 represents a front elevation, and Fig. 3 represents an end elevation, of the 20 same. Fig. 4 represents a cross-section of the machine, partly shown in elevation. Fig. 5 represents a detail side elevation of one of the sprocket-wheels, its chain, and endless apron.

25 Similar letters refer to similar parts wherever they occur on the different parts of the drawings.

In the drawings, A A represent the end frames, secured together at a proper distance 30 apart by means of suitable stays or braces. In a bearing in one of said frames is journaled the driving-shaft B, preferably driven by belt-power applied to a pulley on said shaft, and to the latter is secured a pinion b, the 35 teeth of which mesh in the teeth of a spur-gear C, loosely journaled on a stud C', secured to one of the end frames. The teeth of the spur-gear C mesh in the teeth of the pinions D and E, which are secured to the respective horizontal shafts d and e, journaled 40 in preferably vertically-movable bearings arranged in the end frames A A, as shown.

F is an intermediate gear driven by the spur-gear C. Said intermediate gear F is 45 journaled on a pin or stud f, secured to one of the end frames, and has its teeth meshing in the teeth of a pinion G, secured to a horizontal shaft g, journaled in preferably vertically-movable bearings arranged in the end 50 frames A A, as shown.

To the rotary shaft d are secured sprocket-wheels D' D', from which a rotary motion is

conveyed to similar sprocket-wheels D'' D'' at the opposite end of the machine, as shown. The sprocket-wheels D'' are secured to a shaft 55 d', journaled in preferably vertically-movable bearings arranged in the end frames of the machine.

D³ D³ are endless sprocket-chains by which a rotary motion is conveyed to the sprocket-wheels D'' from the sprocket-wheels D', as shown.

To the sprocket-chains D³ D³ is secured an endless apron consisting of lateral metal bars d³ d³, secured to the links of the chains in any 60 suitable manner. Below the said endless apron is arranged a stationary flat steam-chest D⁴, between which and the under side of the said apron the cloth to be mangled or ironed is carried. Such flat steam-chest is 65 provided with steam supply and return pipes for the purpose of heating the same to the proper temperature as required during the mangling or ironing process.

Between the top and bottom of the endless 70 apron above described are located a series of vertically-movable gravity-rollers d⁴ d⁴ d⁴ for the purpose of holding the under side of the apron as well as the cloth to be mangled or ironed in proper contact with desired pressure 75 against the top of the steam-chest, so as to obtain a great and superior finish on the cloth during the mangling or ironing operation. The size and weight of such rollers 80 may vary according to the pressure desired, 85 or they may be dispensed with altogether—as, for instance, the endless apron may be of sufficient weight so as to produce the same effect.

In practice the bars d³ d³ are covered or 90 padded on their outside with cloth, felting, &c., so as to serve as a cushion to relieve the pressure on the goods in a manner similar to ordinary ironing-tables, so as to produce in this machine work similar to or superior to 95 ordinary handwork. In Fig. 5 we have shown such padding or cushion as consisting of a series of flexible strips d⁵ d⁵, attached in a suitable manner to each individual bar d³ and lapping over one or more of the succeeding bars, as shown. In a like manner to the shaft g (which is arranged below the steam-chest D⁴) are secured sprocket-wheels G', from 100 which a rotary motion is conveyed to similar

- 5 sprocket-wheels G'' , secured to a shaft g' , preferably journaled in vertically-movable bearings in the end frames A A, by means of sprocket-chains $G^3 G^3$, to which the endless 45 apron, composed of the metal bars $g^3 g^3$, (shown in dotted lines in Fig. 4,) is connected, like the bars d^3 on the chains D^3 , hereinabove described. In connection with said endless apron we use a series of vertically-movable 50 gravity-rollers $g^4 g^4$, like the ones hereinabove described, and below said apron is arranged a flat steam-chest G^4 , like the steam-chest D^4 on the uppermost mangle or ironing device.
- 15 Below the steam-chest or flat steam-heated ironing-table G^4 are arranged the rotary sprocket-wheels $E' E''$, secured to the respective shafts $e e'$ and provided with sprocket-chains E^3 and apron-bars e^3 , with hollow flat 55 steam-chest E^4 , like corresponding parts hereinabove described. To the front of the steam-chest D^4 is secured a guide-plate D^5 for properly guiding the articles to be mangled or ironed between the endless apron d^3 and the flat steam-chest D^4 , as shown in Fig. 4. At the rear end of said steam-chest D^4 is secured a downwardly-projecting guide-plate D^6 for guiding the cloths onto the endless apron g^3 . To the rear end of the steam-chest G^4 is secured a guide-plate G^5 for guiding the cloths between the apron g^3 and steam-chest G^4 . To the front end of said steam-chest G^4 is secured a guide-plate G^6 for guiding the cloths onto the apron e^3 .
- 20 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000
- During the operation of the machine the

cloths are taken in a damp condition directly from the extractor or wringer, and by being passed between the successive traveling aprons and their steam-heated flat chests 45 such cloths are caused to be automatically dried, mangled, or ironed on both sides, as described. It will be noticed that as the cloths pass from one apron and steam-chest to another in the series they are reversed—that is, the position of such cloths is reversed—causing them to be dried, ironed, or mangled on both sides.

What we wish to secure by Letters Patent and claim is—

1. In a mangle or ironing-machine, the combination with a series of flat steam-tables arranged horizontally one above the other, of sprocket-wheels arranged at the opposite ends of the tables, endless metallic aprons carried 60 by said sprocket-wheels in contact with the upper sides of the tables, and reversely-curved rigid guide-plates fixed to the opposite ends of the tables and operating to guide the cloths from beneath one apron and deliver them 65 under another, substantially as described.

2. An apron for mangles or ironing-machines, comprising endless chains, metallic bars arranged transversely and secured to said chains, and flexible strips attached to 70 the outer sides of said bars and overlapping each other and said bars at their free ends, substantially as described.

In testimony whereof we have hereunto set our hands in presence of two subscribing witnesses.

ARTHUR L. WING.
ANDREW NORTON.
